LLP(57) **CLAIM**

The ornamental design for a chair, as shown and described.

DESCRIPTION

FIG. 1 is a perspective view of a chair from the front right side thereof, the perspective view from the front left side of the interior of the chair being a mirror image thereof;

FIG. 2 is a perspective view of a chair from the rear right side thereof, the perspective view from the rear left side interior being a mirror image thereof;

FIG. 3 is a front view thereof;

FIG. 4 is a rear view thereof;

FIG. 5 is a left side view thereof;

FIG. 6 is a right side view thereof; and,

FIG. 7 is a top view thereof.

The bottom view of the chair does not form part of the design.

The broken lines of the chair base in the drawings show environmental subject matter only and form no part of the claimed design.
